(57) **CLAIM**

The ornamental design for laboratory apparatus, as shown and described.

DESCRIPTION

FIG. 1 is a front and side perspective view of our laboratory apparatus according to our new design;

FIG. 2 is a front elevation view thereof;

FIG. 3 is a rear elevation thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines showing portions of the laboratory apparatus are included for the purpose of illustrating environmental structure and form no part of the claimed design. The dot-dash broken lines shown in all figures represent the boundaries of the claimed design and form no part thereof.
